William Dupuis, INVENTOR.

BY

Geo. P. Kimmel, ATTORNEY.

UNITED STATES PATENT OFFICE.

WILLIAM DUPUIS, OF POLSON, MONTANA.

CUFF LINK.

Application filed May 6, 1924. Serial No. 711,421.

To all whom it may concern:

Be it known that I, WILLIAM DUPUIS, a citizen of the United States, residing at Polson, in the county of Lake and State of 5 Montana, have invented certain new and useful Improvements in Cuff Links, of which the following is a specification.

This invention relates to cuff links and has for its primary object the provision, in a manner as hereinafter set forth, of a cuff link of such construction that the cuff to which it is attached may be drawn over the hand of the wearer without removing the links therefrom, the links having an inherent 10 means which allows for the expansion and contraction of the parts for the accomplishment of this object.

A further object of the invention is the provision, in a manner as hereinafter set forth, of a cuff link so constructed that the same may be applied to a cuff with a minimum amount of trouble, and when applied may be locked in applied position to prevent the accidental removal of the links 15 from the cuff.

A still further and final object of this invention is the provision, in a manner as hereinafter set forth, of a cuff link of simplified construction, sturdy and serviceable, 20 of neat appearance and inexpensive to manufacture.

The invention will be best understood from a consideration of the following detailed description taken in connection with 35 the accompanying drawings forming part of this specification, with the understanding, that the invention is not confined to any strict conformity with the showing of the drawings, but may be changed and modified 40 so long as such changes and modifications mark no material departure from the salient features of the invention as expressed in the appended claims.

In the drawings:

45 Figure 1 is a perspective view of the device embodying this invention.

Figure 2 is an enlarged detail view of a cuff, showing the device embodying this invention applied thereto, and in longitudinal section.

50 Figure 3 is a side elevation of the cuff link showing the outer portions thereof in the position assumed by them for projection through the button holes of the cuff.

55 Figure 4 is a sectional view upon the line 4-4 of Figure 2.

Figure 5 is a side elevation of one of the members of the cuff link showing the means for locking the two sections of the member together.

60

Figure 6 is a side elevation of one of the members of the cuff link showing the resilient connecting means between the links.

Referring now to the drawings in detail, wherein like numerals of reference indicate 65 corresponding parts throughout the several views, a shirt cuff is indicated at 1 showing the meeting edges 2 which are adapted to be connected together by the cuff links, these meeting edges or sides of the cuff being provided with the usual cuff button holes 3.

The device embodying this invention comprises a pair of opposed inner substantially elongated parallel members 4 and 5, respectively, normally drawn together by a 75 V-shaped spring member 6 interposed therebetween, the free ends of which spring member are secured by means of rivets or other appropriate securing means 7, as clearly shown in Figure 2 of the drawings. This 80 spring member 6 is formed by bending a substantially elongated flat spring metal strip upon itself, the completed spring, being, as shown, of substantially the same length as the members 4 and 5. The natural 85 tendency of this spring is to draw the members 4 and 5 inwardly so that the portions 2 of the cuff will be always retained in close relation. As may be clearly seen in Figure 2, the members 4 and 5 and the 90 interposed spring 6 are located between the portions 2 of the cuff.

Each of the members 4 and 5 has extending laterally from each side edge, at the central portion thereof, arms 8, these arms being parallel as shown and adapted to extend through the button holes 3 upon their respective sides of the cuff member. Extending parallel with each of the members 4 and 5 and in alignment therewith are outer members 9 and 10 respectively, each of these outer members 9 and 10 being divided in half as at 11, and these halves are joined together by means of hinge members 12, which are secured to the edges of the members 9 and 10, and the hinge ears extend outwardly from the face of each of the members 9 and 10 as is clearly shown. These outer members 9 and 10 are adapted to be positioned between the arms 8 and the free ends of the arms 8 are secured thereto by means of the pivot pin 13 of the hinge mem-

bers 12. As is clearly shown in Figure 2 the divided hingedly connected members 9 and 10 are located upon the outer side of the cuff body, the arms 8 which extend through the button holes 3 being the connecting medium for the inner and outer members.

The inner face of one of the halves of each of the outer members 9 and 10 is provided with an undercut notch 14, and the other half of each of the outer members 9 and 10 has secured thereto adjacent the hinge 10, a spring finger 15, this spring finger being adapted to extend across the hinge joint and engage in the notch 14 of the adjacent half of the member to secure the halves in aligned position as is shown in Figure 2.

If reference will be made to Figure 3 of the drawings, the manner in which the cuff link is applied will become clear. As shown, when about to apply the link member, the halves of the outer portions 9 and 10 are brought together as is shown in this figure, and the opposed halves projected through the button holes 3 upon their respective sides. This positions the members 4 and 5 between the cuff sections and leaves the folded outer members 9 and 10 extended through the cuff and upon the outside thereof. The members 9 and 10 are then opened outwardly until the spring fingers 15 engage in the notch 14 upon the adjoining section of each of the members whereupon the same will be retained in open position and it will be impossible for the link to be removed from the cuff. Through the action of the spring 6 between the connected members 4 and 9 and 5 and 10, it may be seen that the connected members may be sprung apart to allow for the passage of a hand through the cuff without the necessity of removing the cuff link from the cuff.

The members 4 and 5 and 9 and 10 of this cuff link may be made of any material which will take design and owing to the shape of the member a very attractive design may be applied thereto, so that the cuff link may be made a very attractive piece of jewelry.

Having thus described my invention what I claim is:

1. In a cuff link of the character set forth, two pair of spaced aligned members, means adapted to extend through the button hole of a cuff for connecting the members of each pair, and means to provide a resilient connection between said two pair of members.

2. In a cuff link of the character set forth, a pair of inner members, a pair of outer members, means for connecting certain of said inner members to certain of said outer members, and means to provide a resilient connection between said inner pair of members.

3. In a cuff link of the character set forth, a pair of inner members, a pair of outer members, means for connecting certain of said inner members to certain of said outer members, and means to provide a resilient connection between said inner pair of members, said outer members being foldable upon themselves for extension through the button hole of a cuff.

4. In a cuff link of the character set forth, a pair of inner members, a pair of outer members each divided in two sections, means for hingedly connecting said sections together, means for connecting each of said inner members to an outer member, and means to provide a resilient connection between said inner pair of members.

5. In a cuff link of the character set forth, a pair of inner members, a pair of outer members each divided in two sections, means for hingedly connecting said sections together, means for connecting each of said inner members to an outer member, and means to provide a resilient connection between said inner pair of members, said outer members being foldable upon themselves for extension through a button hole of a cuff, and means for locking said hinged sections in opened position.

6. In a cuff link of the character set forth, a pair of substantially elongated flat inner members, a pair of substantially elongated flat outer members, means for connecting each of said inner members to an outer member, and means to provide a spring connection between said inner members.

7. In a cuff link of the character set forth, a pair of substantially elongated flat inner members, a pair of substantially elongated flat outer members, each divided in two sections, means for hingedly connecting said sections together, means for connecting each of said inner members to the hinge between the sections of an outer member, and means to provide a resilient connection between said inner pair of members.

In testimony whereof, I affix my signature hereto.

WILLIAM DUPUIS.
